UNITED STATES PATENT OFFICE

GEORGE MERVIN MCGUIRE, OF LOS ANGELES, CALIFORNIA

METHOD OF PRODUCING MARBLEIZED FLEXIBLE SHEETS

No Drawing.

Application filed September 23, 1927. Serial No. 221,615.

My invention relates to a method of finishing and decorating flexible sheets, preferably paper, by producing on the surface thereof marbleized effects so that the treated sheets 5 may be utilized for various artistic and decorative purposes, the principal object of my invention being to provide a relatively simple and easily practiced method, whereby sheets of material such as paper, thin cardboard or 10 oil cloth may be very rapidly treated so as to marbleize the surfaces thereof or produce on the surfaces an arrangement of coloring matter that very closely resembles natural marble.

15 A further object of my invention is to provide a marbleizing method of the character referred to that entirely eliminates all printing, painting or graining operations, thereby enabling the marbleized sheets to be very 20 economically produced, which latter result is of great economic advantage where a large number of the treated sheets are to be produced.

With the foregoing and other objects in 25 view my invention consists briefly in the provision of a bath, in which sheets of paper or the like are immersed so as to absorb or pick up certain of the ingredients from said bath including coloring matter, thereby producing on said sheets the marbleized effect.

In practicing my improved method, I make use of a suitable container, preferably a tank that is adapted to contain water to which is added alcohol, the amount of the latter being 35 approximately one-thirtieth of the total volume of water.

The compound that is utilized with the bath composed of water and alcohol for producing the marbleized effect on the sheets is composed 40 of approximately ten pounds of white lead ground in oil and thinned with turpentine of sufficient quantity of producing a gallon of the mixture. To this gallon of mixture is added approximately one-sixtieth in volume 45 of raw or boiled linseed oil about one-thirtieth by volume of benzol, about one-fifteenth by volume of acetic acid about one-hundredth part by volume of a suitable drier, preferably japan, approximately one-fortieth by volume 50 of hypo-sulphite and sufficient pigment or col-

oring matter to produce the desired color and effect.

The various ingredients just mentioned are thoroughly mixed with the base of white lead and turpentine, and when sheets of paper or the like are to be treated a small quantity of the base mixture is, with a brush or the like, thrown with a quick or whipping motion onto the surface of the bath, and immediately thereafter a sheet of paper is positioned flat- 60 wise upon the surface of the bath and immersed slightly below the surface thereof, and then drawn upwardly with a sweeping motion out of the bath and said sheet is the laid aside to dry. 65

The sheet is immersed in the bath for only a very short period of time, but on contact with the surface of said bath, the sheet absorbs and picks up the base compound including the pigment or coloring matter, and within a few seconds after it has been withdrawn from the bath it is dry and ready for further treatment or use. 70

In some instances, hydro-chloric acid may be used instead of acetic acid, but in either 75 case the acid causes the compound that is thrown onto the surface of the bath to spread over the surface of the bath so as to be engaged by the paper when immersed therein, the hypo-sulphite acts on the paper so that 80 the same readily receives the compound including the coloring matter and the benzol penetrates the paper and causes the coloring matter to adhere thereto. The drier or japan sets the oil that carries the color and assists 85 materially in the drying action.

The alcohol that is combined with the water that forms the bath on which the coloring material is floated, is utilized for the purpose of neutralizing the oil used in grinding the 90 white lead and thus the oil is prevented from forming globules on the surface of the bath when the paper is immersed therein and which globules, if permitted, form undesirable spots on the treated paper. 95

Immediately after the sheets have been immersed in the bath and withdrawn therefrom the action of the air oxidizes the colored surface thereof, thereby setting the colors and the sheets are now ready for use. 100

5 The sheets may be applied to frames or forms through the use of ordinary paper-hanger's paste, or said sheets may be used for various decorative purposes, for instance, for the covering of fancy boxes, for decorating windows or for wrapping gift packages or the like.

10 Ordinary manila paper may be treated by my improved method so as to produce marbleized surfaces and by coating the sheets of paper with black, red, green, or blue coloring material soluble in alcohol and to which is added shellac or imitation shellac, the sheets are given a colored back ground upon which 15 marbleized effects may be produced when said sheets are immersed in the bath.

15 The sheets after being applied for use may be varnished or coated with shellac thereby materially adding to the appearance of the 20 marbleized surfaces and adding depth thereto as well as producing the effect of a polished marble surface.

25 Thus it will be seen that I have provided a relatively simple and easily practiced method, whereby sheets of paper or the like may be easily and quickly marbleized and consequently producing a very desirable and attractive surface finishing product.

I claim as my invention:

30 1. The herein described method of marbleizing flexible sheets which consists in immersing flexible sheets in a bath composed of water and alcohol and having on its surface a compound containing white lead, a vegetable 35 oil and coloring substance.

2. The herein described method of marbleizing flexible sheets which consists in immersing flexible sheets in a bath composed of water and alcohol having on its surface a 40 compound containing white lead, a vegetable oil, acid and coloring substance.

3. The herein described method of marbleizing flexible sheets which consists in immersing flexible sheets in a bath composed of 45 water and alcohol having on its surface a compound containing white lead, a vegetable oil, a drier and coloring substance.

4. The herein described method of marbleizing flexible sheets which consists in immersing flexible sheets in a bath composed of water and alcohol having on its surface a compound containing white lead, a vegetable oil, benzol and coloring substance.

5. The herein described method of marbleizing flexible sheets which consists in immersing flexible sheets in a bath composed of water and alcohol having on its surface a compound containing white lead, a vegetable 60 oil, hypo-sulphite and coloring substance.

6. The herein described method of marbleizing flexible sheets which consists in immersing flexible sheets in a bath composed of water and alcohol having on its surface a compound containing white lead, a vegetable 65 oil,

oil, an acid, benzol, hypo-sulphite and a coloring substance.

7. The herein described method of marbleizing flexible sheets which consists in immersing flexible sheets in a bath composed of water and alcohol and having on its surface a compound comprising white lead, a vegetable oil, benzol, acid, a drier, hypo-sulphite and a coloring substance.

80 In testimony whereof I affix my signature.
